[57] CLAIM

The ornamental design for a fuel dispensing unit, as shown and described.

DESCRIPTION

FIG. 1 is a right front perspective view of a fuel dispenser showing our new design;

FIG. 2 is a front elevational view thereof;

FIG. 3 is a right side elevational view wherein the left side is similar in appearance to the right side;

FIG. 4 is a left rear perspective view thereof; and,

FIG. 5 is a top plan view thereof.

The broken line showing the bottom portion and hoses of the fuel dispensing unit in all of the drawing figures is for illustrative purposes only and forms no part of the claimed design.
